CONTROL SYSTEM FOR INTERNAL-COMBUSTION ENGINES.

1,186,037.

Specification of Letters Patent.

Patented June 6, 1916.

Application filed December 18, 1911, Serial No. 666,324. Renewed June 25, 1915. Serial No. 36,411.

To all whom it may concern:

Be it known that I, FREDERICK PURDY, a citizen of the United States, residing at Kenosha, in the county of Kenosha and 5 State of Wisconsin, have invented certain new and useful Improvements in Control Systems for Internal-Combustion Engines, of which the following is a specification.

The general object of my invention is to 0 provide means for improving the operation and efficiency of internal combustion engines wherein the ignition-time is controllable and the fuel supply is regulable,—as is the case in the modern gas engine, 5 equipped with the ordinary throttle and with electrical sparking appliances.

In the following description I will for succinctness use the term "spark" as indicating an ignition agent variable in timing, 10 and the term "throttle" as meaning any suitable means for regulation of the fuel supply.

My invention consists in novel means of ignition-time control for such internal combustion engines; in novel means of regulation of the charge-volume; in the coordination of a charge regulating means with an ignition-time controlling means; and in provision for the automatic governing of the controlling instrumentalities.

In the operation of an internal combustion engine, an appreciable interval of time is required for the propagation of the flame in an explosive mixture of given volume, such time varying, roughly speaking, inversely with "fuel density"—so to term the relative number of combustible particles per unit of volume in the compressed charge,—and also inversely with the density of the air in which the particles are suspended. With a given richness of mixture (within working limits, of course), the time moment of flame propagation varies, therefore, generally inversely in accordance with the compression of the charge, by reason of the effect of compression variations upon both the fuel density and the air density. And with constant compression, the time moment of flame propagation varies, of course, generally inversely with the richness of the mixture and the consequent variations of fuel density.

In the operation of the modern gas engine, it is customary to "advance the spark"—that is, to cause the ignition spark to be 55 made before the engine piston reaches the end of its compression stroke,—and to vary the "advance" or "lead" of the spark generally in accordance with the engine speed variations, in order that the working pressure in effecting its rapid rise due to combustion may be most efficiently applied substantially as the engine crank passes dead center and the piston starts on its working stroke. Generally speaking, therefore, the 60 faster the engine runs, the farther the spark must be advanced, for during a given time interval of flame propagation the crank will travel through a greater angle at high speed than at low speed. This variation of the 65 spark time, if it is to be directly proportional to the engine speed, may be effected by a suitable speed-responsive device, actuated by the engine and controlling appropriate spark-initiating or spark-distribut- 70 ing mechanism.

I have found, however, that spark-time control by a mere engine speed-responsive device, as above suggested, does not fulfil all requirements of automatic spark-time 80 regulation for most efficient and economical operation of the engine.

In the operation of the ordinary gas engine, when a light load is being carried, the engine is throttled to a greater or less extent, and a smaller charge is drawn into the engine cylinder than is the case where the engine is working under a heavy load and the fuel supply conduit is correspondingly more fully opened. Consequently, 90 there is a smaller volume of gaseous fuel to compress and a lower compression under the light load than under the heavy load conditions, and the spark-time adjustment proper for a lightly loaded engine at a 95 given speed causes too early an ignition in a heavily loaded engine at the same speed owing to the decreased time of flame propagation under the conditions of greater fuel density and higher compression. Conversely, of course, a proper spark-time advance for a heavy load would occasion too late an ignition for a light load. Therefore, compensation in the spark-time adjustment,

effected by the speed-responsive device, should be made in harmony with the adjustment of the throttle or other fuel-regulating device, in order that the spark may 5 be advanced or retracted not only in accordance with variations in engine speed, but also accordingly as the throttle condition is favorable to lower or higher fuel density.

Furthermore, when the ordinary gas engine 10 is running under a constant load, increase of the engine speed tends to result in decrease of the fuel density and compression as the quantity of the fuel drawn into the cylinder against the resistance of the carburetor and the throttle is less than when the engine is running slowly.

To meet the requirements for efficient spark-timing in a throttle-controlled engine, imposed by these underlying considerations, 20 I provide time-regulating means for the spark which is under the control, jointly, of an engine speed-responsive device and of the fuel-regulating device or throttle, so that the tendency of the speed-responsive device to 25 advance or retract the spark accordingly as the engine speed is increased or decreased will be modified by the compensating adjustment for advancement or retraction of the spark accordingly as the throttle-valve opening 30 is decreased or increased in size.

It may also be deemed advantageous in the operation of a gas engine to maintain a uniform critical compression, as nearly as possible, at all engine speeds, and it is therefore 35 advantageous so to regulate the charge-volume by the introduction of air into the engine cylinder that the charge volume (and therefore the compression) may tend to remain uniform under different speed conditions and throttle adjustments. Therefore, as a matter of advantage *per se*, as well as 40 conjointly with the spark-time control, I make provision of a charge-regulating means comprising a valve for admitting air 45 to the engine cylinders (preferably locating the valve in the fuel passage between the throttle and engine), said valve being regulable by the action of an engine-speed-responsive device, preferably modified by the 50 action of the device responsive to the throttle adjustment.

It will be apparent that where the spark advances in accordance with the increases in engine speed and further in accordance 55 with decreases in the throttle area, the spark will be further advanced when the engine is running under light load (with relatively closed throttle) at a given speed than when the engine is running under heavy load (with 60 relatively open throttle) at the same speed. When the engine is running at slow speed under heavy load, both the wide opening of the throttle and the slow speed of the engine tend jointly to cause retraction of the 65 spark and when the engine is running under

light load at high speed, the controlling actions of both the throttle and speed-responsive means jointly tend to produce advance of the spark. In short,—the spark-time is regulated in harmony jointly with the speed 70 of the engine and with the condition of the fuel control means, which governs primarily the fuel density.

The regulation of the auxiliary air component of the charge in harmony with the speed 75 of the engine and preferably with the condition of the throttle, tends to the production of uniform compression of the charge in the cylinder under all speeds and under all conditions of fuel regulation, for uniform maintenance of the most effective compression.

Thus, when the engine is running at high speed under light load (with the spark far advanced and the throttle partly closed), the auxiliary air passage is sufficiently opened to allow the engine to supplement the fuel supply with air drawn through the auxiliary air valve so that the volume of the charge may be substantially as great as that taken in when the engine 80 is running under heavy load (with the throttle opened, the spark retracted, the air valve closed, and the entire charge taken through the carburetor). These coincident adjustments of the air-regulation valve and the 85 spark-timing means tend to provide economical operation. At high speed under light load the fuel content of the charge is minimized and the spark far advanced. Under heavy load at high speed, when the 90 throttle is widely opened, the tendency of the speed-responsive device to advance the spark is offset somewhat by the tendency of the throttle-controlled means to retract the spark and the air content of the charge is 95 decreased. These automatic adjustments of the spark-timing and auxiliary air supply relate back to their initiation, directly or indirectly, to the throttle adjustment, and if desired, the throttle adjustment itself may be 100 controlled by a speed-responsive device, operated by any part which it is desired to run by the engine at predetermined speed. Thus, by associating with the engine shaft itself a speed governor controlling the throttle, 105 uniform engine speed under varying loads, with the most economical operating conditions, may be insured; or by association of such governor with the wheel shaft of a vehicle driven by the engine, predetermined 110 vehicle speed may be maintained with the fuel supply, the charge-regulator, and spark-timing adjustments, all automatically varied, for economical compensation for variations in the resistances met by the vehicle 115 in maintaining its predetermined speed.

In the drawings, wherein I have illustrated an embodiment of my invention, for the purposes of disclosure, Figure 1 shows in outline a well known type of internal com- 120

bustion engine, and a diagrammatic illustration of the application of devices thereto for the embodiment of my invention; Fig. 2 is a vertical cross section, on line 2—2 of Fig. 3, of a governor; Fig. 3 is a horizontal section on line 3—3 of Fig. 2; Fig. 4 is a detail of an auxiliary air-controlling valve; and Fig. 5 is a schematic view of the regulator appliances.

10 In Fig. 1, 6 indicates in outline an engine of which 7 is the main shaft and 8 a driven counter shaft. 9 indicates the fuel-intake pipe. 10 a carbureter. 11 a throttle valve between the carbureter and engine intake port, and 12 a spark distributor, these parts being all conventionally shown.

15 indicates in general a speed-responsive device which in the specific embodiment shown (Figs. 2 and 3) comprises a main shaft 16, driven by a miter gear 17 from the counter shaft 8, and at its upper end, within a shell 18, bearing a head 19, which supports a transverse shaft 19' having mounted thereon a heavy ring 20, so arranged that when 20 the main shaft 16 is rotated, centrifugal action tends to swing the ring about its pivotal axis until it lies in approximately a horizontal plane. On the transverse shaft 19' are mounted two segmental gears 21 meshing 25 with rack members 22 guided by brackets 23 of the head 19 and cross connected by a transverse bracket 22'. As the transverse shaft 19' rocks, obviously, the racks will cause the bracket 22' to be raised and lowered.

30 In direct alinement with the shaft 16 is a rod 25 having ball bearing connection 26 with the bracket 22', and extending upward through a spring casing 27, which is located 35 in an extended neck 18' of the shell 18. The rod 25 has fixed thereto a collar 29, which affords bearing for the governor spring 30, abutting at its upper end against a follower 31, which loosely surrounds the rod 25, and 40 has a sliding keyed connection 32 with the spring casing 27 to prevent rotation of said follower.

45 Means to regulate the biasing spring resistance to the governor movement are provided as follows: The follower 31 has its upper edge formed into a crown cam 33 engaged by a similar cam 34 rotatable on the rod 25 and held in firm engagement with the cam 33 by a cap member 35 which is secured to the casing neck 18'. Beyond the cap member 35, the cam 34 has a lever arm extension 37 by which it may be rotatively moved, thereby to exert a cam action on the follower 31 to move it vertically and so to 50 change the tension of the spring 30. This lever arm 37 has appropriate connection (Fig. 5) by a rod 38 with the fuel control operating crank 11' for the throttle 11, so that as the crank 11' is rotated to open the 55 throttle, crank 37 is rotated to increase the

governor spring tension or biasing effect and vice versa, so that the governor may have maximum spring resistance when the throttle is fully opened and minimum spring resistance when the throttle is closed.

At its projecting upper end, the rod 25 has connection with the horizontal arm of a bell-crank lever 40, suitably mounted on the engine, and the vertical arm of said lever is connected by a link 41 to the relatively shiftable element of the spark-distributer 12, in such fashion that the higher the end of the rod 25 rises, the farther the spark is advanced. (See Fig. 5).

Now, it will be apparent that as the speed of the engine increases or decreases, the action of the ring 20, communicated through rod 25, tends to effect the spark distributer correspondingly to advance or to retract the spark, but the spring tension opposing the action of the ring is dependent upon the throttle condition, such spring tension increasing as the throttle is opened and decreasing as it closes. The desirability of these adjustments is apparent from a consideration of the conditions preliminarily discussed.

The auxiliary air-supply regulator may conveniently take the form of an air valve 50 in the fuel conduit 9, having connection with the engine-speed-responsive device to be automatically opened as the speed increases and moved toward closed position with decrease in speed. It is my preference that the same speed-responsive device controlling the auxiliary air valve shall be subject to and modified by throttle control, and therefore, I operate the air valve from the speed-responsive device 15 heretofore described. 51 indicates a link connection between the tail 50' of the valve 50 and the vertical arm of the bell crank lever 40, such connection causing the auxiliary valve to open wider as the bell crank is rocked by the governor in response to increase in speed modified by the throttle.

The throttle lever 11' may be provided with an operating rod 55, leading to any suitable point of control, either manual or automatic. For some purposes, it is advantageous that the rod 55 be connected, for actuation, to a speed-responsive governor 56, driven by a suitable shaft 57, the speed of which may accord with any suitable part driven by the engine,—either the engine shaft 7 itself or a traction wheel or shaft of the automobile, or the like. The governor 56 may have its spring abutment 58 shiftable manually as by the operation of cam 60 upon the stem 59 of said abutment, the cam 60 being operable in any suitable fashion from a remote point, and the arrangement shown being, of course, diagrammatic.

It will be apparent, that with any given setting of the spring of governor 56, the lat-

1
ter will tend to maintain in the engine conditions producing such predetermined speed in said governor. As the resistance to the engine driven part actuating said governor 5 tends to decrease the governor speed, the governor tends to open the throttle for the production of an increase in fuel density, with a commensurate retraction of the spark, thereby to maintain the set speed. In- 10 versely, a decrease in the resistance to the engine-driven part, tends to increase the speed of the governor, but is met by a closing movement of the throttle with a commensurate spark advance. Manifestly, in 15 stationary engine work, by actuating governor 56 in harmony with the rotation of the engine shaft, substantially uniform speed may be maintained under varying load conditions through the operation of the gov- 20 ernor 56; while in automobile practice, by relating the governor 56 to a traction wheel or shaft, the governor will tend to produce in the engine at all times conditions resulting in the desired vehicle speed. Obviously, 25 by manual control of the governor spring, variations in the predetermined set speed may be effected.

It will now be manifest that by proper adjustment of the spark time in accordance 30 jointly with the throttle condition and the engine speed automatic adaptations in ignition timing compensating for variations in density, or density and compression, of the charge are effected, and that by suitable automatic adjustment of the auxiliary air-supply 35 valve, the compression is maintained approximately constant under varying conditions,—all to the end of accomplishing maximum work with minimum fuel by causing flame propagation to take place under 40 conditions as nearly as possible ideal.

What I claim is:

1. The combination with an internal combustion engine having regulable fuel-control 45 means and sparking means, of means includ- 50 ing opposed regulable means and speed-re- 55 sponsive means and a part to be moved by the force of one said means over that exerted by the opposing means to regulate the timing 60 of the spark in harmony jointly with the speed of the engine and the position of the fuel-control means.

2. The combination with an internal combustion engine having regulable fuel-control 55 means and sparking means, of an engine speed-responsive means, and means to vary the movement of the speed-responsive means at given speed in harmony with the fuel control means for varying the spark-time 60 controlled jointly by the said speed-respon- 65 sive means and the fuel-control means.

3. The combination with an internal combustion engine having regulable fuel-control 65 means and sparking means, means respon- 70 sive to engine speed and variably resisted in

such response by the fuel-control means, and spark-timing means controlled by said speed-responsive means so governed.

4. The combination with an internal combustion engine having regulable fuel-control 70 means and sparking means, means responsive to engine speed and variably modified in such response by the fuel control means, and spark-timing means controlled by said speed responsive means so modified. 75

5. The combination with an internal combustion engine having regulable fuel-control means and sparking means, of an engine-speed responsive means having an adjustable part, means connecting said speed 80 responsive means and said spark-timing means, means connecting said adjustable part with the fuel-control means for adjusting the spark timing means in harmony with the condition of the fuel-control means 85 and the speed responsive means.

6. The combination with an internal combustion engine having regulable fuel-control means and sparking means, of an engine-speed responsive means having a resistance-adjusting part, means connecting said resistance-adjusting part with the fuel-control means for adjustment in harmony 90 with the condition of the fuel-control means, and spark-timing means controlled by said speed-responsive means. 95

7. The combination with an internal combustion engine having regulable fuel-control means and sparking means, of a spark-timer, an engine-speed governor having a 100 spring-adjusting means, operative connec- 105 tions between said spring-adjusting means and the fuel-control means to vary the gov- 110 ernor spring tension as the condition of the fuel-control means is varied, and connec- 115 tions between the spark-timer and governor to advance the spark as the governor over- 120 comes the spring resistance.

8. The combination with an internal combustion engine having regulable fuel control means and sparking means, of an automatic spark governing device including a speed responsive means and means operable when said fuel control means is operated to modify the operation of said speed responsive means to control the relative time of the spark. 110

9. The combination with an internal combustion engine having a regulable fuel-control means, of spark-timing means therefor, and a differential governor having connec- 120 tions respectively with the fuel-control means, an engine moved part, and said spark-timing means, for adjusting the timing means an amount determined by the speed of the engine varied by an amount de- 125 termined by the condition of the fuel-control means.

10. An apparatus for association with an 130 internal combustion engine, a fuel throttle,

and spark-timer, comprising a part automatically movable by variation of engine operation for moving said spark-timer; a connection between said automatically movable part and said timer, including an adjustable part, and means movable in harmony with the throttle to adjust said part whereby to change the rate of movement of said timer, as the fuel charge, or load, is varied by said throttle.

11. The combination with an internal combustion engine having regulable fuel control means, and a spark varying means, of a spark-time controller comprising a part driven in time relation with the engine; a biased part movable by variation of speed of said engine; variable means for opposing the movement of the latter part; a connection between the biased part and the spark varying means, and means operable when the fuel control means is operated for actuating said variable opposing means.

12. The combination with an internal combustion engine, of spark-timing means, fuel-control means, and an automatic governing device therefor including a movable part connected to said timing means, centrifugal means tending to move said part in one direction, and means, operated by said fuel-control means, for exerting an opposing tendency against the centrifugal means to render said centrifugal means subject to said fuel-control means.

13. The combination with an internal combustion engine, having regulable fuel control means and sparking means; of means, including opposed regulable means connected with the fuel control means and speed responsive means, and a part to be moved by the force of said speed-responsive means over that exerted by the opposing means to regulate the timing of the spark in harmony jointly with the speed of the engine and the position of the fuel control means.

14. The combination with an internal combustion engine having a fuel-supply means and an auxiliary air-supply means, of means for regulating the auxiliary air supply including an engine-speed-responsive device, controlled by means for controlling the fuel supply means.

15. The combination with an internal combustion engine having a regulable fuel-control means and an auxiliary air-supply means, of means for regulating the auxiliary air-supply responsive jointly to the engine speed and the condition of the fuel-supply means.

16. The combination with an internal combustion engine having regulable fuel-control means and sparking means, of means to regulate the timing of the spark in harmony with the fuel density of the compressed charge, and means to maintain

constant compression of the charge under varying speeds.

17. The combination with an internal combustion engine having regulable fuel-control means and sparking means, of means to regulate the timing of the spark in harmony with the engine speed and the condition of the fuel-control means, and means to maintain constant compression of the charge under varying speeds.

18. The combination with an internal combustion engine having regulable fuel-control means and sparking means and means to admit an auxiliary air supply governed jointly by the speed of the engine and said fuel control means.

19. The combination with an internal combustion engine having regulable fuel-control means and sparking means, of spark-timing means, auxiliary air-supply means, and an automatic governing device, including a speed-responsive governor dominated by said fuel control means for varying the operation of the spark-timing means and auxiliary air-supply means.

20. The combination with an internal combustion engine having regulable fuel-control means and sparking means, of spark-timing means, auxiliary air-supply means, an automatic governor device actuated by the engine and controlled accordingly to the condition of the fuel-supply means, means for control of said sparking means by said governor, and means for control of said auxiliary air-supply means by said governor, thereby to tend to preserve uniformity in compression and to adjust the spark time to both engine speed and fuel density.

21. The combination with an internal combustion engine having fuel-control means, of spark-timing means, automatic means to adjust the fuel-control means in harmony with the engine speed, and means to adjust the spark-timing means in harmony jointly with the condition of the fuel control means and the speed of the engine.

22. An apparatus for association with an internal combustion engine to automatically control the spark as the load varies, comprising a fuel throttle; a spark-timer; a part, movable by operation of the engine for moving the said timer, and means movable when said throttle is moved, to vary the rate of movement of said timer, when automatically moved by said engine movable part.

23. The combination with an internal combustion engine having fuel control means and spark timing means, of means including a speed responsive device for adjusting the fuel control means; means including an engine-speed-responsive device for adjusting the spark timing means; connections between said speed responsive devices and means operable by first mentioned speed re-

sponsive device to modify the second mentioned speed responsive device in accordance with adjustment of said fuel control means.

24. The combination with an internal combustion engine having fuel-control means, of spark-timing means, auxiliary air-supply means, means including a speed-responsive device for adjusting the fuel-control means, and means including an engine-speed-responsive device for adjusting the spark-timing and auxiliary air-supply means.

25. The combination with an internal combustion engine of a carburetor; a fuel throttle for said carburetor; controlling means therefor; a spark-time controlling means; a speed-responsive means operated by said engine connected to said spark timing means, and a connection between said throttle controlling means and said speed responsive means adapted and arranged to modify the operation of said speed responsive means when said throttle is adjusted.

26. The combination with an internal combustion engine having a carburetor and regulable fuel control means therefor and variable sparking means, of an engine speed responsive means and connections between said devices whereby to modify the action of said speed responsive means when the fuel admission opening of said carburetor is adjusted.

27. The combination with an internal combustion engine, a carburetor; a controlling means therefor; a spark-time controlling means; a speed-responsive governor, and connecting means between said carburetor, controlling means and speed responsive governor, to modify the operation of said governor when the fuel admission opening of said carburetor is adjusted.

28. The combination with an internal combustion engine, a carburetor, a controlling means therefor, a spark-time controlling means, a centrifugal governor, operated by the engine, and connecting means between said carburetor controlling means and said governor, to modify the operation of said governor when the fuel admission opening of said carburetor is adjusted.

29. The combination with an internal combustion engine, a carburetor having an auxiliary air-supply means, a fuel throttle, for said carburetor, controlling means therefor, a spark-time controlling means, a centrifugal governor operated by said engine connected to said air-supply means and to said spark-timing means, and a connection between said carburetor throttle-controlling means and said centrifugal governor adapted and arranged to modify the operation of said governor when said throttle is adjusted.

30. The combination with an internal combustion engine having regulable fuel-

control means and sparking means, of spark-timing means, auxiliary-air-supply means, a part movable in joint response to changes in engine speed and fuel-control, and connections between said part and the spark-timing means and auxiliary air-supply means, respectively.

31. The combination with an internal combustion engine having regulable fuel-control means and sparking means, of spark-timing means, an engine-speed governor having connection to said spark-timing means, and connections between said fuel control means and said governor, to effect reduction or increase in the movement thereof, and, through the connections between said governor and spark-timing means, in the spark-time for said combustion engine.

32. The combination with an internal combustion engine, having regulable fuel-control means and sparking means, of means responsive to engine speed and variably resisted in such response by the fuel control means, spark timing means controlled by said speed responsive means; a second engine speed responsive means operatively connected with the regulable fuel-control means and means for varying the resistance of the second speed responsive means.

33. The combination with an internal combustion engine, having regulable fuel-control means and sparking means, of means responsive to engine speed and variably resisted in such response by the fuel control means, spark timing means controlled by said speed responsive means, and a second engine speed responsive means operatively connected with the regulable fuel control means.

34. The combination with an internal combustion engine, having regulable fuel-control means and sparking means; of means including opposed, regulable means connected with the fuel control means and speed responsive means and a part to be moved by the force of said speed responsive means over that exerted by the opposing means to regulate the timing of the spark in harmony jointly with the speed of the engine and the position of the fuel-control means; and an engine speed responsive means operatively connected with the regulable fuel control means.

35. The combination with an internal combustion engine, having regulable fuel-control means and sparking means; of means including opposed regulable means connected with the fuel control means and speed responsive means and a part to be moved by the force of one said speed responsive means over that exerted by the opposing means, to regulate the timing of the spark in harmony jointly with the speed of the engine and the position of the fuel control means; an engine speed responsive

means operatively connected with the regulable fuel control means; and means for varying the resistance of the last mentioned speed responsive means.

- 5 36. An apparatus for association with an internal combustion engine having a spark timer and an intake throttle comprising, a speed responsive member; a connection between said member and spark-timer where-
10 by the time of ignition is varied by move-
ment of the member and means associated
with the throttle to modify the operation of
said member for further affecting the time
of ignition.
- 15 37. In combination, an internal combus-
tion engine; a movable part, operable by
the engine in accordance with varying con-
ditions of engine operation; a fuel throttle;
20 a spark-timer; connections between said
timer and said engine-movable part for ad-
justing the spark-time, by movement of said
part, and means connected for operation in
harmony with throttle movement arranged

to modify the action of said engine-mov-
able part on said timer to vary the rate of 25
spark time adjustment when said throttle is
moved.

38. In combination with an internal com-
bustion engine; a movable part, operable by
the engine in accordance with the conditions 30
of engine operation: a fuel-throttle, for
varying the volume of fuel charges; a spark-
timer; connections between said timer and
said engine-movable part, including an ad-
justable part to vary the ratio of movement 35
of said timer, and means, operable in ac-
cordance with throttle movement, to control
said adjustable part to change the rate of
movement of said timer in harmony with
the conditions of fuel charge. 40

In testimony whereof I hereunto set my
hand in the presence of two witnesses.

FREDERICK PURDY.
